UNITED STATES PATENT OFFICE.

JOHN E. THORNTON, OF ALTRINGHAM, AND JAMES P. LEA, OF MANCHESTER,
ENGLAND.

OIL-FEEDING DEVICE FOR EXPLOSION-ENGINES.

SPECIFICATION forming part of Letters Patent No. 664,981, dated January 1, 1901.

Application filed January 4, 1899. Serial No. 701,152. (No model.)

To all whom it may concern:

Be it known that we, JOHN EDWARD THORNTON, residing at Altringham, in the county of Chester, and JAMES POLLARD LEA, residing at Hulme, Manchester, in the county of Lancaster, England, subjects of the Queen of Great Britain, have invented certain new and useful Improvements in Apparatus for Supplying a Charge of Oil, of which the following is a specification.

The invention is designed to provide apparatus for measuring a charge of oil or like liquid with extreme accuracy and great rapidity.

The invention consists in applying a force-pump to fill a measuring-port of defined capacity formed in a slide-valve, such pump taking oil from a reservoir and returning excess thereto through a measuring-port which retains a measured charge, and in forcibly projecting the measured charge of oil from the measuring-port by a pressure of air at one end of the port superior to that at the other end, and the novel effect produced by this combination is the accurate and very rapid measurement and delivery of successive charges of oil and the practicability of situation of the measuring device in relation to the hot vaporizer to which it is connected as to work under sufficiently favorable conditions of coolness, so as to avoid clogging and other defects.

The invention will be fully described with reference to the accompanying drawings.

Figure 1 is a sectional elevation of the apparatus. Fig. 2 is a sectional plan on line *x y* of Fig. 1. Fig. 3 is a sectional elevation showing a modification. Fig. 4 is a sectional elevation in a vertical plane at right angles to Fig. 3. Fig. 5 is a sectional elevation showing another modification: Fig. 6 is a sectional plan showing modification of Fig. 4 with slide-valve flat and auxiliary air-compressing plunger. Fig. 7 is a section showing alternative arrangement of the parts.

The oil-valve A is in this instance in the form of a plunger sliding to and fro in a casing or cylinder B, closed at one end and fitted at the other with a gland C, through which the plunger A passes and closes it. The oil-valve A is reciprocated by a crank or cam

eccentric D on a rotating shaft d, connected to it by a connecting-rod d'.

In the oil-valve A are formed two ports or passages *a a'*, preferably passing diametrically through it, one of which, *a*, receives and measures the charge of oil and the other, *a'*, serves as a passage for the oil to the suction or measuring pump E. The port *a* is of exact capacity to receive the required charge of oil to be measured, and the other, *a'*, and forcing-pump E may be of any capacity so long as the pump throws a quantity of oil in excess, and advantageously much in excess, of the capacity of port *a*.

The cylinder or casing B is provided with an air port or passage *b*, leading from the closed end of the cylinder, through which the air compressed therein by the upward stroke of the oil-valve can be discharged, and a port or passage *b'*, diametrically opposite the discharge-orifice of the port *b*, leading to or to be connected with the vaporizer of an oil-engine. The cylinder B is also provided with a passage or chamber *f*, connected by pipes *f' f''* with an oil-reservoir F, and diametrically opposite it with a port or passage *e*, leading to the oil-pump E. Through the cylinder B is also formed an air-inlet aperture or port *b''*, through which a fresh charge of air is admitted to the top closed end of the cylinder at each backward stroke of the oil-valve A.

A suction-pump E to draw oil from the oil-reservoir is fitted to the side of the cylinder B. This pump is constructed of a flexible diaphragm *e'*, to which a piston-rod E' is attached. The piston-rod is connected to the valve-operating rod by a connecting-link and pivoted lever.

The ports *a* and *a'* in the oil-valve A are so situated relatively to the passages *b b'* and *f* in the cylinder or casing B that when the valve A is at the end of its forward stroke the measuring-port *a* is in communication with the air-passage *b* and discharge-passage *b'* and port *a'* is in communication with the oil-passages *f* and *e*, and when the oil-valve A is at the end of its backward stroke the measuring-port *a* is in communication with the oil-ports *e* and *f*.

In the modification shown in Figs. 3 and 4 a second or auxiliary cylinder H is connected

by port *h* with the closed end of the cylinder *B* to supply a greater volume of compressed air, or the cylinder *H* may be employed alone to compress the air.

5. In the modification shown in Fig. 5 the compressed air necessary to project the charge of oil from the determinate port *a* of the oil-valve is supplied from an air vessel *K*, into which air is forced by any suitable form of air pump or compressor.

Referring to Fig. 7, the arrangement shows the second or suction port in the slide-valve replaced by a self-acting inlet or suction valve *K'*, controlling the oil-passage *k* to the pump. The action is similar to that already described, the pump drawing oil from the reservoir through the valve *K'* and forcing the excess back to the reservoir through the passage *e*, measuring-port *a*, and pipe *f'*.

20. In operation, the measuring-port *a* in the oil-valve *A* being charged with oil on the forward stroke of the plunger *A*, the air is compressed in the closed end of the cylinder *B* and air-passage *b*. On the valve reaching

25. the end of its stroke the measuring-port comes between and connects the air-passage *b* and the discharge-passage *b'*, leading to the vaporizer of the motor, and the compressed air forcibly or violently impels the measured

30. charge of oil contained in the port *a* into the passage *b'*, leading to the motor, in the form of a fine spray or jet mixed with air. At the same time, a stroke or pulsation of the pump *E* having taken place, oil flows or is drawn

35. from the reservoir *F* and port *f* through the oil-port *a'* into the passage *e*, leaving the pump *E* and passage *e* fully charged with oil. On the downward stroke of the oil-valve *A* the ports in the cylinder or casing are first

40. closed and the air-inlet aperture *b*² is uncovered, admitting a fresh charge of air to the closed end of the cylinder. At the end of the downward stroke of the oil-valve or plunger *A* the measuring-port *a* comes between and

45. connects the oil-passages *f* and *e*, and the return stroke or pulsation of the pump *E* forces oil through and leaves a charge of oil in the measuring-port *a*, displacing the air therein, which passes back into the oil-passage *f'* and

50. escapes to the top of the oil-reservoir *F*. The cycle of operation is then repeated at each stroke of the oil-valve *A*.

What we claim as our invention, and desire to protect by Letters Patent, is—

55. 1. Apparatus for measuring at a rapid rate a charge of liquid combustible with great exactitude comprising in its construction a container for the liquid combustible, a pump connected therewith by a single port for forcing 60 or inducing a flow of the liquid combustible at intervals to and fro, a slide-valve with two sets of ports formed therein one of defined capacity and the other of convenient size and a valve-casing with four sets of passages terminating in it which communicate the first set with the pump, the second set with the oil-container such passages being so placed

that both sets of ports in the valve alternately come between and connect them to permit of the flow of liquid to and fro between the pump and the container, the third set with the oil-receiver and the fourth set with an air-compressor through which compressed air is delivered to project the oil charge from the measuring-port such port being connected at intervals substantially as described.

2. In apparatus for measuring at a rapid rate a charge of liquid combustible the combination with a container for the liquid combustible a slide-valve with a measuring-port formed therein through which excess of oil passes back to the reservoir and which retains a measured charge of oil and a casing inclosing the oil-valve provided with suction 85 and delivery ports of a force-pump connected with the oil-container and with the suction and delivery ports by which a flow of oil is induced at intervals substantially as described.

3. In apparatus for measuring at a rapid rate a charge of liquid combustible with great exactitude comprising in its construction a container for the liquid combustible a pump connected therewith for forcing or inducing 95 a flow of the liquid combustible at intervals to and fro, a slide-valve with two sets of ports formed therein one of defined capacity and the other of convenient size and a valve-casing with passages terminating in it and 100 cam mechanism for actuating the slide-valve and pump in correct relation to each other substantially as described.

4. In apparatus for measuring at a rapid rate a charge of liquid combustible with great 105 exactitude the combination with a container for the liquid combustible a slide-valve provided with two sets of ports formed in it the one of defined capacity and the other of any desired size of a pump for forcing a flow of 110 the liquid at intervals to and fro and a valve-casing provided with ports therein through which the liquid flows and double diverging passages one through which air escapes connecting with the top of the container and the 115 other through which the supply of liquid flows connecting with the bottom of the container substantially as described.

5. In apparatus for measuring at a rapid rate a charge of liquid combustible with great 120 exactitude the combination with a container for the liquid combustible a slide-valve provided with two sets of ports formed in it the one of defined capacity the other of any desired size of a pump for forcing a flow of the 125 liquid at intervals to and fro and a valve-casing closed at one end in which a charge of air is compressed provided with ports through which the liquid flows and a port connecting the closed end of the casing with the measuring-port of the valve through which the compressed air projects the charge of oil out of the measuring-port substantially as described.

6. Apparatus for measuring a charge of liq-

uid combustible fuel and injecting it with rapidity and exactitude into the vaporizer of an oil-engine or into another receptacle comprising in its construction, a slide-valve 5 provided with two sets of ports formed in it, the one of determinate capacity and the other operating to permit the flow of liquid to and fro, a force-pump and cam operating the same in timed conjunction with the slide-valve, a reservoir containing a supply of the liquid combustible at a suitable head of pressure a casing provided with two sets of openings leading to the vaporizer or other receptacle and the other to the closed end of the casing 15 in which a charge of air is compressed, the

ports being placed opposite so that the determinate part in the slide-valve may come between and connect them and the other set of ports leading respectively to the force-pump and the reservoir and connected intermittently by the ports in the slide-valve substantially as described. 20
